(57) **CLAIM**

I claim the ornamental design for trapway for a sink, as shown and described.

DESCRIPTION

FIG. 1 is a top perspective view of a trapway for a sink embodying the invention.

FIG. 2 is a bottom perspective view of the trapway for a sink shown in FIG. 1.

FIG. 3 is a front view of the trapway for a sink shown in FIG. 1.

FIG. 4 is a bottom view of the trapway for a sink shown in FIG. 1.

FIG. 5 is a rear view of the trapway for a sink shown in FIG. 1.

FIG. 6 is a left side view of the trapway for a sink shown in FIG. 1; and,

FIG. 7 is a right side view of the trapway for a sink shown in FIG. 1.

The broken line showing of the environment is for illustrative purposes only and forms no part of the claimed design. The broken lines which define the boundaries of the claimed design form no part thereof.
